(57) **CLAIM**

The ornamental design for a top cover of vacuum cleaner as shown and described.

DESCRIPTION

1. Top cover of vacuum cleaner

1.1 : Top

1.2 : Enlarged

1.3 : Front

1.4 : Enlarged

1.5 : Back

1.6 : Left

1.7 : Right

1.8 : Enlarged

1.9 : Top

1.10 : Bottom

1.1 is a perspective view of a top cover of vacuum cleaner; the vacuum cleaner can be hand-held in use; 1.3 and 1.5 are front and back views thereof; 1.6 and 1.7 are left and right views thereof; 1.9 and 1.10 are top and bottom views thereof; 1.2, 1.4 and 1.8 are enlarged views of parts A, B and C boxed and marked in 1.1, 1.3 and 1.7, respectively; The

(Continued)

broken lines in the reproductions depict portions of the top cover of vacuum cleaner that form no part of the claimed design.
